UNITED STATES PATENT OFFICE.

GEORGE D. HILL, OF NORFOLK, VIRGINIA.

SHADE, CURTAIN, OR AWNING ROLLER STOP.

Application filed April 17, 1922. Serial No. 553,657.

To all whom it may concern:

Be it known that I, GEORGE D. HILL, a citizen of the United States, and a resident of Norfolk, in the county of Norfolk and State 5 of Virginia, have invented certain new and useful Improvements in Shade, Curtain, or Awning Roller Stops, of which the following is a specification.

This invention relates to stops especially 10 adapted for use in connection with shade, curtains, awnings or the like and is an improvement over the construction illustrated in my United States Patent Number 1,166, 683.

15 Briefly stated, the improvement residing in this application is in the nature of an attachment which may be readily and conveniently connected to one end of a shade, curtain or awning roller so as to limit the 20 rotation of the roller and consequently provide a reliable means whereby to limit the movement of the shade or the like when drawn downwardly.

25 A further object is to provide a roller attachment which may be inserted into one end of the roller and connected to an ordinary bracket in such a manner that the major portion of the attachment is concealed.

30 While the invention is illustrated in the drawing as employed in connection with a shade, it is quite obvious that the inventive idea involved may be employed in connection with a curtain, awning or other body 35 which is wrapped about a roller.

The invention forming the subject matter of this application also aims to provide an attachment which is of highly simplified construction, durable in use and cheap to 40 manufacture.

Other objects and advantages of the invention will be apparent during the course of the following description.

In the accompanying drawings forming 45 a part of this application and in which like numerals are employed to designate like parts throughout the same,

Figure 1 is a side elevation of the attachment in use.

50 Figure 2 is a longitudinal sectional view through the same applied.

Figure 3 is a group perspective of the attachment and a portion of a roller.

55 Figure 4 is a perspective of a collar embodied in the invention.

Figure 5 is a plan view of the blank from which the collar is formed.

Figure 6 is a sectional view illustrating a slightly modified form of the invention, the shade and roller also being shown in 60 section.

Figure 7 is a group view of the construction illustrated in Figure 6.

Figure 8 is a group perspective of the form of the invention illustrated in Figures 65 6 and 7.

In the drawing, the numeral 5 designates a roller having one end formed with a pintle 6 to which the attachment is 70 adapted to be connected.

As previously stated, the attachment is adapted to limit the movement of the roller and to this end I provide a spindle 7 having one end formed with an enlargement 8 provided with a socket 9. As illustrated in 75 Figure 3, the socket 9 has one side flat to correspond to the flat side 10 of the pintle 6 and when the pintle is received within the socket 9 a driving connection is provided. It will be seen, however, that the pintle 6 is 80 of the ordinary construction and that the flat side 10 may be provided by means of a file thereby enabling the spindle 7 to be detachably connected to the pintle.

A spiral body 11 is mounted on the spindle 85 and has one end portion 12 extended through a slot 13 in the spindle whereby the spiral body which may be in the nature of a coil spring is securely connected to the spindle and is thereby caused to rotate therewith. 90 The other end of the spiral body 11 is formed with a return bend 14 which serves as a stop element for a collar designated by the numeral 16.

The collar is mounted upon the spiral 95 body and is formed with a pair of inwardly extending lugs 17 adapted to fit between the convolutions of the spiral body so that when the spiral body is rotated the collar will be moved longitudinally of the spindle. Of 100 course, one of the inwardly directed lugs is arranged slightly in advance of the other lug as illustrated in Figure 4.

The collar 16 is formed from the blank 105 illustrated in Figure 5 wherein the blank is shown as being provided with extensions which are interlocked in the manner illustrated in Figure 4 to define a radial rib or member 19 which is received within a longitudinally extending slot 20 in a tubular 110

housing 21. As the radial rib 19 is received within the slot 20 the collar 16 is, of course, held against rotation so that when the spiral body is rotated the collar will be moved longitudinally. The slot 20 extends out through the end of the housing 21 adjacent the roller and consequently permits the spindle, the spiral body, and the collar to be withdrawn as a unit. When the parts 10 11, 16 and 21 are withdrawn, the collar 16 may be manually adjusted on the spiral body so as to limit the movement of the fabric body 23 tacked or otherwise secured to the roller. If it is desired to allow only a slight 15 movement to the fabric body 23 the collar 16 may be positioned somewhat close to the return bend 14 as illustrated in Figure 2, and if it is desired to increase the zone of movement of the body 23 the collar is positioned near the outer end of the spindle. It 20 will be apparent, of course, that the return bend 14 serves as a stop element for limiting the longitudinal movement of the collar.

In summarizing, it will be observed that 25 the attachment may be readily and conveniently connected to the roller without a substantial alteration in the construction of the roller and it will be further seen that the appearance of the roller or the body 30 carried thereby is not marred. A bracket 25 may be formed integral with the housing 20 or may be detachably connected thereto. The bracket serves as a convenient means for securing the roller and the attachment 35 to a suitable support such as a window frame.

If desired, the invention may be built into the roller 40 in the manner illustrated in Figures 6 to 8 inclusive in which figures 40 the fabric body 41 is shown wound about the roller.

The housing 42 which is of tubular formation is inserted into a socket in one end of the roller and the housing has one end 45 formed with a radial attaching flange 43 formed with claws 44 which bite into the roller and thereby anchor the tubular housing in position. A spindle 45 is received within the tubular housing 42 and is provided with a spiral body 46 about which a 50 collar 47 is arranged. In this form of the invention the collar is provided with a radial rib 48 which is received within a longitudinally extending slot 49 in the tubular housing whereby the rotation of the 55 spindle and the spiral body results in the movement of the collar longitudinally of the housing.

In carrying out this form of the invention 60 one end of the spindle 45 is extended a short distance beyond the tubular housing and is squared as indicated at 51 for engagement with a bracket 52. The squared end 51 of

the spindle is received within a squared opening 53 in the bracket and consequently the 65 spindle is held against rotation so that when the roller is rotated the collar will be moved longitudinally of the housing.

In carrying out the invention, the spindle 45 may be provided between the bracket 52 70 and the tubular housing with an annular flange 63 which serves as a means to hold the spindle in position.

In operation, the collar 47 is set at the proper position on the spiral body 46 and when the fabric body 41 is pulled its movement will be limited by the collar engaging the return bend 55 on the spiral body. 75

It will be seen that the attachment, when applied, is practically concealed and further 80 that it does not in any way interfere with curtains which may be arranged close to the shade.

The foregoing illustrates that this invention 85 is capable of a variety of mechanical expressions and it is therefore understood that such minor changes in arrangement and construction of parts may be made as will remain within the spirit of the invention and 90 the scope of what is claimed.

Attention is directed to the fact that the coil springs 11 and 46 have their ends formed with returned bends which constitute stop elements and limit the movements 95 of the members 16 and 47 respectively. It will be seen that the coil springs yield to a limited extent when the collars are engaged with the said elements, and therefore, a yieldable means is provided to limit the downward movement of the shade. By providing a yieldable stop for the shade the shade cannot be accidentally pulled off the roller. 100

I claim:—

1. The combination with a roller having 105 a socket, of a spindle received in said socket, a convolute spring secured on said spindle and having one end free and formed with a return bend, and a collar mounted on said spring having lugs engaging the convolutions of the convolute spring.

2. The combination with a roller having 110 a socket, of a spindle received in said socket, a convolute spring secured on said spindle and having one end free and formed with a return bend, a collar mounted on said spring having lugs engaging the convolutions of the convolute spring, and a housing arranged in said roller and receiving said spindle and said convolute body. 115

3. The combination with a roller having 120 a socket, of a spindle received in said socket, a convolute spring secured on said spindle and having one end free and formed with a return bend, a collar mounted on said spring having lugs engaging the convolutions of 125

the convolute spring, and a housing arranged in said roller and receiving said spindle and said convolute body, said housing having means holding said collar against turning.

4. The combination with a roller having a socket, of a spindle received in said socket, a convolute spring secured on said spindle and having one end free and formed with a 10 return bend, a collar mounted on said spring having lugs engaging the convolutions of the convolute spring, and a housing arranged in said roller and receiving said spindle and said convolute body, said housing being provided with a longitudinal slot receiving a portion of said collar to hold the collar against turning.

5. In a stop member for rollers, a collar formed from a single blank of metal having 20 its ends formed with extensions bent into interlocking relation whereby to define a rib, said collar having lugs integral therewith and adapted for driving engagement with the convolutions of a coiled spring.

25 6. The combination of a roller having one end formed with a socket, of a housing received in said socket and having a slot, a spindle received in said housing, a coiled spring mounted on said spindle, a collar mounted on the spindle and having a rib received in said slot, and a bracket supporting said spindle, said spring having a return bend constituting a yieldable stop element 30 in the path of travel of said collar.

35 7. The construction set forth in claim 6, said spindle being non-rotatably connected to said bracket.

8. The construction set forth in claim 6, one end of said housing being provided with

an anchoring member adapted to engage 40 the roller.

9. An attachment for shades comprising a tubular housing adapted to be received in one end of a roller and concealed thereby, a 45 spindle received in said tubular housing and having one end extending beyond the tubular housing, yieldable means associated with said spindle for limiting the rotation of the roller, and a flange formed on said spindle and engaging said housing for limiting the 50 endwise movement of the spindle.

10. The construction set forth in claim 9, and a bracket having connection with the extended portion of said spindle, the spindle being non-rotatably connected to the bracket. 55

11. An attachment for shade rollers comprising a spindle, a coiled spring mounted on the spindle and having one end anchored thereto and its other end free and formed with a return bend, a collar mounted on 60 said spring and having a lug engaged by and arranged between the convolutions of the spring, and a housing having a longitudinal slot, said collar being provided with a radial member received in said slot. 65

12. An attachment for shade rollers comprising a spindle, a coiled spring mounted on the spindle and having one end anchored thereto and its other end free and formed with a return bend, a collar mounted on 70 said spring and having a lug engaged by and arranged between the convolutions of the spring, and a housing receiving said spring and said spindle, said collar being provided with a sliding and rotatable connection with said housing. 75

GEORGE D. HILL.
